OILS FOR TWO-CYCLE ENGINES CONTAINING BASIC AMINO-CONTAINING DETERGENTS AND ARYL HALIDES

George J. Benoit, Jr., San Anselmo, Calif., assignor to Chevron Research Company, a corporation of Delaware
No Drawing. Filed Sept. 8, 1964, Ser. No. 395,032
9 Claims. (Cl. 252—51.5)

This invention concerns lubricating oils useful primarily in two-cycle engines. More particularly, this invention concerns lubricating oils containing aryl halides and amino-containing lubricating oil detergents.

Since the advent of the second World War, the use of the two-cycle engine has proliferated. With the increase in the numbers of motorcycles, motorscooters, chainsaws, lawnmowers, and outboard engines for recreation and commercial boating, the two-cycle engine has secured a place as a prime power source. Despite the popularity and wide distribution of the two-cycle engine, no effort has been made on a broad commercial scale to provide a gasoline tailored to the two-cycle engine's needs. Rather, the efforts of the industry have been directed toward providing an oil which, when combined with gasoline used for automobiles, would be adapted to the requisites of the two-cycle engine.

The presence of the oil admixed with the gasoline increases the tendency for deposits to collect in the exhaust port and piston crown. The presence of the lead compounds which are usually present in gasoline, leads to spark plug fouling, particularly electrode bridging. Additives are therefore included in the oil to minimize the problems of deposits and spark plug fouling. It is essential that the additives do not interfere with each other's respective functions. That is, the various additives in the oil must not react or interact with each other, so as to reduce their effectiveness or deleteriously affect the oil's properties.

Pursuant to this invention, lubricating oil compositions are provided which are stable for long periods of time and minimize formation of deposits and spark plug fouling, which have an amino-containing amide or imide as the lubricating oil detergent, and an aryl halide as the scavenger.

The amount of halohydrocarbon used in the lubricating oil composition will vary with the particular halohydrocarbon used, the desired degree of performance, the particular fuel with which the lubricating composition is to be mixed, and the proportion in which the fuel and lubricating oil composition is mixed. Preferably, the amount of aryl halide used is such that the final fuel/lubricating mixture will contain between about 2 to 5 theories, more preferably between about 2.5 to 4 theories of halide. Generally, the amount of aryl halide in a lubricating oil composition will be between about 0.1 and 5 weight percent, preferably between 0.5 and 3 weight percent.

When the lubricating oil composition is added to a conventional leaded gasoline, it increases the theories of halide available in the gasoline. All conventional leaded gasolines already contain in addition to the alkyl lead compound, some organohalide to act as a scavenger for the lead. Commonly, about 1 to 1.5 theories of halide are present in such gasolines. While this amount of halide scavenger is about sufficient to deal with deposit problems in a 4-stroke internal combustion engine, it is not adequate in a 2-stroke engine, which is run on a mixture of fuel and lubricant. The effect of incorporating the lubricating oil composition to this invention in fuels for 2-stroke engines is to enhance the available theories of halide, thus minimizing the deposit problem, particularly with spark plugs.

2

The term "theory" is used in the industry to mean the quantity of organohalide required in the fuel or fuel/lubricant mixture to convert (theoretically) all the lead present as tetraalkyl lead into a corresponding lead halide.

5 Although tetraethyl lead is the most popular tetraalkyl lead used, the present compositions may be used with any fuel mixture which contains any of the commonly used tetraalkyl lead compounds, e.g., tetramethyl lead, methyltriethyl lead, etc. While the fuel/lubricant mixtures may contain from about 0.1 to 5 cc./gal. of the tetraalkyl lead, the usual amount of tetraalkyl lead will be in the range from about 1 to 3 cc./gal., and more usually about 1.5 cc./gal.

10 The amount of the amine detergent which is used in the base oil will be from about 0.5 weight percent to about 10 weight percent, more usually about 2 to 7 weight percent.

15 The aryl halides used in this invention are those from about 6 to about 16 carbon atoms, preferably 6 to 12 carbon atoms, having from one to two aromatic rings, either fused or nonfused. Each ring may have from about 1 to 3 halogen substituents of atomic number 17 to 35, i.e., chlorine and bromine; preferably, the aromatic molecule will have a total of from 1 to 4 halogens, particularly preferred, 2 halogens. The aromatic ring may be substituted with lower alkyl groups, i.e., alkyl groups of from 1 to 6 carbon atoms.

20 Illustrative compounds within the above description are chlorobenzene, bromobenzene, o-, m-, p-chlorotoluene, o-, m-, p-bromotoluene, 2-chloro-1,3-xylene, 4-chloro-1,3-xylene, 2-bromo-1,3-xylene, 4-bromo-1,3-xylene, 4,6-dichloro-1,3-xylene, 4,6-dibromo-1,3-xylene, 2,5-dibromo-1,4-xylene, 2,5-dichloro-1,4-xylene, 2-bromo-5-chloro-1,4-xylene, 1,2-dibromobenzene, 1,2-dichlorobenzene, 1,4-dibromobenzene, 1,4-dichlorobenzene, 1-bromo-4-chlorobenzene, 2,4-dibromocumene, 4,4'-dibromobiphenyl, etc.

25 Also included in the lubricating oil is the carboxamide or imide of a polyamine. These lubricating oil detergents are reported in a number of domestic and foreign patents, e.g., U.S. Patents Nos. 2,922,708, 3,018,291, 3,024,237, 3,110,673, and French Patent No. 1,265,086. The polyamine will have from 2 to 6 amino groups and a molecular weight in the range from about 60 to about 40 30 35 40 45 50 55 60 65 70 75 80 85 90 95 100 105 110 115 120 125 130 135 140 145 150 155 tions thereof, but are preferably aliphatic. Depending on the structure of the particular acids and amines used in the reaction, amides, imides or imidazolines may be formed.

The preferred monocarboxylic acids will generally be of from 5 to 30 carbon atoms, preferably from 12 to 20 carbon atoms. Such acids are exemplified by caprylic acid, capric acid, lauric acid, myristic acid, palmitic acid, stearic acid, arachidic acid, oleic acid, linoleic acid, abietic acid, etc.

The preferred dicarboxylic acids are the alkenyl succinic acids. Usually, they are used in the reaction as anhydrides, i.e., alkenyl succinic anhydrides, having the following formula:

wherein R is an alkenyl group most conveniently obtained by polymerizing an olefin having from about 2 to 5 carbon atoms. The molecular weight of the resulting polymer would generally be in the range of about 400 to 3000, more usually in the range of about 900 to 1200. Useful olefins are illustrated by ethylene, propylene, 1-butene, 2-butene, isobutene, 1-pentene, and mixtures thereof, preferably isobutene. The methods of polymerizing such olefins to the polymers of the designated molecular weight are well known in the art and do not require exemplification here. As for preparing the alkenyl succinic anhydrides by reaction of the polyolefin and maleic anhydride, this reaction has been repeatedly published in numerous patents, e.g., U.S. Patents Nos. 3,018,250 and 3,024,195.

When referring to carboxylic acids, it is intended to include carboxylic acids and derivatives which will react with amines to form amides, imides or imidazolines. These acyl derivatives include acyl halides, carboxylic acids, anhydrides and esters. The preferred carboxylic acid derivatives are the carboxylic acid itself and the anhydride. However, in particular instances, the other derivatives may find use. The esters which find use are lower alkyl esters, e.g., methyl, ethyl and propyl.

Depending upon the particular carboxyl or acyl derivative used in the reaction with the polyamine, the temperature will range from about 200° F. to about 500° F., more usually from about 275° to 450° F. The pressure used in the system will generally be atmospheric, although in specific instances higher or lower pressures may be used.

The carboxyl equivalents will be at least one fewer than the number of available primary and secondary amino groups. That is, if X is the number of available amino groups, i.e., primary and secondary, then at least one mole and not more than X-1 mole of carboxylic acid—particularly monocarboxylic acid—will be used per mole of polyamines. The equivalent ratio between carboxyl groups and available amino groups will generally be in the range of about .16 to .8 carboxyl equivalent per available amino group.

When the lubricating oil detergent is a polyamide of the alkylene polyamine:

wherein m is an integer of from 1 to 5 and n is an integer of from 1 to 6, the equivalents of carboxylic acid used will be in the range 1 to n.

The amide or polyamide produced from monocarboxylic acid can be characterized by the following formula:

wherein m and n are as defined previously, R¹ is a carboxyl group of from 5 to 30 carbon atoms, and p is an

integer of from at least 1 and not more than n. When n is from 4 to 5, preferably p is from 2 to 3.

The imide from the alkenyl succinic acid with the alkylene polyamine is characterized by the following formula:

where m, n and R are as defined previously. Preferred n varies from 2 to 5, particularly preferred is n equal to 4.

The formation of the amide or imide may be run in the presence or absence of an inert solvent. Inert solvents or dispersants include aromatic hydrocarbons, aliphatic hydrocarbons, specifically mineral oils of lubricating viscosity, aryl halohydrocarbons, ethers and polyethers, etc.

The reaction time will usually be in excess of two hours and rarely exceed 24 hours. More usually, the reaction time will be in the range of about 3 to 15 hours.

The reaction is usually carried out in an inert atmosphere, such as nitrogen, helium, argon, etc., that is in the absence of oxygen. During the reaction it is generally desirable to distill off the water or alcohol (when using an ester) as it is formed. This can be conveniently done by means of a Dean-Stark trap. Desirably, the pressure of the system may be reduced below atmospheric to facilitate the removal of the water.

The amine lubricating oil detergent and aryl halide may be combined with a variety of lubricating oils. Illustrative lubricating oils are petroleum derived oils or mineral oil, such as naphthenic base, paraffin base and mixed base lubricating oils; synthetic oils, e.g., alkylene polymers (such as polymers of butylene, 1-decene, etc.), polyesters, etc.

The following examples are offered by way of illustration and not by way of limitation.

Example I

A mixture consisting of about 3.7 parts by weight of tetraethylene pentamine (1 mole) and 0.0002 part by weight of a silicone foam inhibitor was charged into a reaction vessel in a nitrogen atmosphere and heated to 250° F. To this mixture was then added 18.2 parts by weight (3 moles) of a hydrocarbon monocarboxylic acid of a narrow equivalent weight range, having an average equivalent weight of 310. The temperature was then raised to 298°-300° F. for a period in excess of one hour, followed by a further increase to 380° F., maintaining the temperature for a period of about 6 to 7 hours, while reducing the pressure to about 28 mm. Hg in order to facilitate the removal of water. At the end of this time, the reaction mixture is cooled, providing the desired basic amino-containing detergent.

Example II

A mixture of 84 g. (0.45 mole) of tetraethylene pentamine and 702 g. (0.45 mole) of a polyisobutylsuccinic anhydride, wherein the polyisobutyl radical was derived from a polyisobutene having a molecular weight of about 1000, was blended with agitation at 125° F. in a nitrogen atmosphere. The temperature was increased to 400° F. over a period of one hour. Then the pressure was reduced to about 2 mm. Hg during a period of 30 minutes. The reaction mixture was allowed to reach room temperature while maintaining the reduced pressure. The reaction product contained about 3.8% nitrogen.

The reaction products from Examples I and II were mixed with aliphatic and aromatic halides, the mixture diluted with a mineral oil and maintained at the specified temperature, the basicity and viscosity being measured

repeatedly. The following Table I indicates the results obtained:

The effect of aging on engine performance was also tested. Oil samples of a solvent refined paraffinic base oil containing 5 weight percent of the detergent of Ex-

³ This base number is essentially that described in method ASTM D-664 except that a larger sample is used, in order to increase the accuracy of the titration.

⁴ 16 days.

The aromatic halides were also tested in an engine. The test employs a model 850 Mercury outboard engine, 6-cylinder, 76 cubic inch, 85 H.P., running at 5000 r.p.m. for 100 hours, wide open throttle. An engine is shut down only for spark plug replacement or mechanical trouble. It consists essentially of three 2-cylinder engines in one block equipped with three carburetors, so that three fuel/oil combinations can be run simultaneously.

The engine is mounted in a tank and is equipped with a special test wheel in place of a propeller. Cylinder head temperatures, water in and out temperatures, engine speed and fuel flow rate are recorded.

At the end of the test, inspections are made on the piston rings, piston ring grooves, land, skirt, head and underhead deposits, intake and exhaust port deposits and cylinder head deposits. Ring sticking is reported as F for free (no sticking) or the arc which is stuck (360° being totally stuck). Piston varnish is rated from 0-10, 10 being completely clean. The other deposits are reported on a rating of 50 as being clean and 0 completely covered.

A 2-cycle engine motor oil was prepared by blending California base SAE 40 base oil containing 5 weight percent of the reaction product of Example I, and 0.68 weight percent of p-dichlorobenzene. This amount of p-dichlorobenzene provided one additional theory of halogen for gasoline leaded to 1.5 cc. per gallon of tetraethyl lead and used at a fuel to oil ratio of 20: 1.

The gasoline with which the above-identified motor oil was blended in the fuel to oil ratio 20:1 had an ASTM D-86 distillation starting point of 95° F., a 50 percent point of 219° F. and an end point of 393° F. The gasoline contained 1.5 cc. of tetraethyl lead per gallon of gasoline and one theory of ethylene dibromide scavenger.

The following Table II indicates the results obtained:

ample I and scavenger in the indicated amounts were aged by heating each sample for about 1 month at 170° F.

The test employed a McCulloch chain saw engine, model No. 1-81, run at maximum power for 10 hours, with a head temperature of 440° F. The feed was a 20/1 volume ratio of fuel to oil.

When the run was completed, the piston was removed and inspected for piston varnish, ring sticking (or degree of deposits in groove, if second ring was not stuck), ring land deposits, underhead deposit and exhaust port plugging. A rating of 0-50 is used with 50 as clean.

The following table indicates the results obtained:

TABLE III

	Scavenger	Weight per- cent in Oil ¹	Overall Engine Rating
Ethylenedibromide		0.86	² 15.6
p-Dichlorobenzene		0.68	38.5
p-Dibromobenzene		1.1	37.3

¹ Equimolar amounts of the scavenger were used.

² The engine was shut down after 6 hours because of excessive deposits.

It is evident that the aryl halides in combination with the polyamine detergents provide excellent results in the two-cycle engines. The engines are kept clean and the rings unstuck under extremely rigorous test conditions. Moreover, both the concentrates and the finished oil composition are stable for long periods of time, retaining their detergent and scavenger ability.

As will be evident to those skilled in the art, various modifications on this process can be made or followed, in the light of the foregoing disclosure and discussion, without departing from the spirit or scope of the disclosure or from the scope of the following claims.

I claim:

1. A 2-cycle engine lubricating oil composition comprising:
a major proportion of an oil of lubricating viscosity, from about 0.5 to about 10 weight percent of a lubricating oil detergent having at least one free amino group and being the reaction product of a hydrocarbon polyamine of from 2 to 6 amino groups and a

hydrocarbon carboxylic acid of from 1 to 2 carboxyl groups and of from 150 to 1500 equivalent weight, reacted at a temperature in the range of 200° to 500° F.,

and from about 0.1 to 5 weight percent of an aryl halide of from 6 to 10 carbon atoms, wherein the halogen of said halide is of atomic number 17 to 35.

2. A 2-cycle engine lubricating oil composition comprising:

a major proportion of an oil of lubricating viscosity; 10 from about 0.5 to 10 weight percent of a lubricating oil detergent of the following formula:

15

wherein m is an integer of from 1 to 5, n is an integer of from 1 to 6, p is an integer of from 1 to n and R^1 is a hydrocarbon carboxacyl group of from 5 to 30 carbon atoms; and from 0.1 to 5 weight percent of an aryl halide of from 6 to 10 carbon atoms, wherein the halogen is of atomic number 17 to 35.

3. A composition according to claim 2 wherein n is 4, and p is an integer of from 2 to 3.

4. A composition according to claim 3 wherein said aryl halide is dichlorobenzene.

5. A composition according to claim 3 wherein said aryl halide is dibromobenzene.

6. A 2-cycle engine lubricating oil composition comprising:

a major proportion of an oil of lubricating viscosity; from about 0.5 to 10 weight percent of a lubricating oil detergent of the following formula:

25

20

30

35

wherein m is an integer of from 1 to 5, n is an integer of from 1 to 6, and R is an alkenyl group having a molecular weight in the range from about 400 to 3000, and from 0.1 to 5 weight percent of an aryl halide of from 6 to 10 carbon atoms, wherein the halogen is of atomic number 17 to 25.

7. A composition according to claim 6 wherein R is an alkenyl group of molecular weight in the range from about 900 to 1200.

8. A composition according to claim 7 wherein said aryl halide is dichlorobenzene.

9. A composition according to claim 7 wherein said aryl halide is dibromobenzene.
